The ornamental design for a probe for an ultrasonic diagnosis apparatus, as shown and described.

(51) **LOC (9) Cl.** **24-01**

DESCRIPTION

(52) **U.S. Cl.** **D24/186**

FIG. 1 is a front, top and left side perspective view of a probe for an ultrasonic diagnosis apparatus, showing my new design;

(58) **Field of Classification Search** D24/107, D24/138, 141, 142, 158, 164, 165, 167, 170, D24/186–187, 200, 231; D10/57, 60, 78, D10/80; 600/407, 461, 459, 447, 439, 446; 378/98.7, 98.8, 189

FIG. 2 is a front, bottom and right side perspective view thereof;

See application file for complete search history.

FIG. 3 is a front elevational view thereof;

(56) **References Cited**

FIG. 4 is a rear elevational thereof;

U.S. PATENT DOCUMENTS

FIG. 5 is a top plan view thereof;

D245,514 S * 8/1977 Pennebaker D24/142
D262,360 S * 12/1981 Aslan et al. D24/200
D300,175 S * 3/1989 Bar-Yam D24/138
4,841,979 A * 6/1989 Dow et al. 600/446
D304,760 S 11/1989 Curtis et al.
D320,078 S * 9/1991 Terwilliger et al. D24/158
D387,867 S * 12/1997 Henderson et al. D24/187
D403,421 S * 12/1998 Cody et al. D24/186
5,897,503 A * 4/1999 Lyon et al. 600/459

FIG. 6 is a bottom plan view thereof;

FIG. 7 is a left side elevational view thereof; and,

FIG. 8 is a right side elevational view thereof.

The broken line showing of the remainder of the probe for an ultrasonic diagnosis apparatus is for illustrative purposes only and forms no part of the claimed design.
